UNITED STATES PATENT OFFICE

EDWIN H. GRAVER, OF CLEVELAND, OHIO, ASSIGNOR TO BELLE B. GELLNER, TRUSTEE,
OF CLEVELAND, OHIO

INCINERATOR

Application filed March 11, 1926. Serial No. 93,827.

This invention is concerned with domestic refuse disposal apparatus and has for its general object the provision of a simple practical garbage incinerator which is adaptable for the incineration of garbage and other waste materials.

A further object of my invention is the provision of a garbage disposal apparatus of the character referred to embodying structural features directed to the trapping of the waste material to be burned in a hot gas passageway of the apparatus to effect a preliminary drying of the material before its final discharge into the fire box.

15 A still further object of my invention is the provision of an incinerator which may be charged with a volume of refuse material which is greatly in excess of the capacity of the fire box without any clogging of the passageways of the incinerator resulting therefrom.

Further objects of my invention will hereinafter be more fully set forth in connection with the description of the accompanying drawings. The essential characteristics are summarized in the claims.

In the drawings Figure 1 is a side elevation of the incinerator embodying the features of my invention; Figure 2 is a front elevation of the incinerator; Figure 3 is a cross-sectional side elevation of the incinerator taken substantially along the line 3-3 of Figure 2; Figure 4 is an enlarged cross-sectional detail taken substantially along the line 4-4 of Figure 3; Figure 5 is a cross-sectional view similar to Figure 4 but taken along the line 5-5 of Figure 3; Figure 6 is an enlarged sectional detail taken substantially along the line 6-6 of Figure 1; Figure 7 is a cross-sectional detail taken along the line 7-7 of Figure 1 and Figure 8 is a cross-sectional elevation of a modified form of an incinerator embodying the features of my invention.

My invention contemplates the provision of an incinerator apparatus for the disposal of garbage, refuse such as paper, and similar waste material which accumulates in apartment buildings, residences, hospitals, etc., and I propose an incinerator construction

which will require a minimum degree of care, be simple in its operation and effective in the disposal of the garbage in a sanitary manner without permitting the escape of noxious odors and gases. It is now common practice to provide incinerators which have some form of trap or primary grate upon which the wet garbage is deposited above the incinerator fire box whereby the garbage may be dried or desiccated before being deposited in the fire box. Such incinerators prove to be efficient in destroying the garbage but they not infrequently become clogged due to an overcharge of materials thereinto.

In my present invention, as shown in cross-section in Figure 3, I provide an inclined shelf, hereinafter described in detail, upon which the garbage is primarily deposited and I associate with this shelf a movable means for agitating the wet garbage and for shifting it to the fire box whereby the masses of wet garbage may be agitated from time to time to permit the hot gases escaping from the fire box to thoroughly contact with each particle of garbage and thereby more effectively remove the moisture therefrom. This arrangement I incorporate in an incinerator stove or furnace and such furnace may be constructed in the basement of 80 the building or apartment to be served thereby.

The furnace proper may comprise an enclosed elongated compartment 12 formed by an outer brick structure 13 which is provided with a suitable fire lining 14. This structure is preferably rectangular in shape to completely enclose a fire compartment and drying compartment and the interior of the structure may be provided with a partition wall 18 extending upwardly to an inclined partition 19. As shown in the drawings the partition 19 is disposed at a higher level than the fire grate 20 supported by an end wall 21 and the partition wall 18 of the incinerator structure in any suitable manner. The fire grate 20 is disposed within the incinerator a suitable distance above the floor thereof to provide an ash chamber or pit 24 and I form in the side wall 26 of the

incinerator structure, doorways leading into the incinerator above and below the grate 20 which may be closed by suitable doors 28 and 30, the former comprising a fire door and the latter an ash door. On one side of these doors I provide exteriorly disposed means in the form of a lever 31 connected in any suitable manner to the grate bars 20 whereby they may be dumped or agitated 10 when desired.

The means for suspending the garbage while it is being dried may comprise an inclined grate or shelf structure 33 disposed immediately above the inclined partition 15 member 19 upon which the wet garbage is deposited through a passageway 34 formed by a charging tube or doorway 35 extending upwardly from the incinerator through the floor 38 of the building in which the incinerator is installed.

The tube 35 may be of such construction that it can extend through the ground floor of the building being served and terminate inside of the incinerator at a position below 25 the top wall of the incinerator structure. It is accordingly provided with a bottom door 36 and a top door 37 whereby the incinerator may be charged by first opening the top door to deposit the material within 30 the tube and by closing the top door and opening the bottom door thus preventing the escape of any noxious gases from the combustion chamber.

To cause the garbage deposited upon the 35 grate shelf 33 to be discharged onto the fire grates 20 and to also afford means for agitating the wet garbage from time to time as it is being dried, I provide a series of movable scraper members 40 in the form of 40 flat blades which are carried by endless chain stretches 42 and 43. These chain stretches extend over sprocket members 45 and 46. The sprocket members are mounted on shafts 47 and 48 and are disposed adjacent the side walls of the incinerator structure whereby the blades 40 may extend substantially across the entire face of the shelf bars 33. The particular disposition of the two shafts relative to the drying grate is 45 such that when one of the shafts is manually rotated, the scraper bars 40 will be carried over the top faces of the bars 33 of the drying shelf or grate and deposit the dried garbage upon the combustion grate 20 and the disposition of the shelf bars 33 relative to 50 the partition 19 is such as to provide clearance therebetween for the passage of the scraper bars 40 beneath the shelf bars 33.

The shelf bars 33, as shown in Figure 5, 55 may extend substantially from side wall to side wall of the incinerator and rest upon suitable bracket members 50 and 51 secured to the side walls of the incinerator and these bracket members may be formed to comprise bearing members for the shafts. The

bars 33 may comprise a single grate casting if desired or a series of grates or a series of groups of cast bars with joining webs 33a to prevent the scraper bars 40 from locking therebetween. 70

The partition 19 is preferably formed of metal whereby the scraper bars 40 may slide thereover without undue wear to the partition structure and one of the shafts, namely, the shaft 47, extends completely 75 through the side wall 26 of the incinerator and through a close fitting bearing tube 58 (see Figure 4) and any convenient means may be mounted on the outer end thereof, preferably a crank member 59, for effecting 80 the manual operation of the scrapers.

Ventilation and draft regulation of the incinerator is provided as follows: The doors 28 and 30 may be provided with the usual draft shutters 28a and 30a respectively, for regulating the amount of air passing into the incinerator above and below the fire grate 20 and in addition thereto I provide an air passageway, (see Figures 1 and 6) 60 extending into the ash pit and two air 90 passageways 61 and 62, one on each side of the fire doorway 28, for additional air to pass into the fire box. One or more of these passageways may be closed by plugs 65, 95 (see Figure 6) if desired.

I also provide a series of observation openings 68 and 69 (see Figures 1 and 7) extending through the side wall 28 of the incinerator at positions above and below the grate shelf 33 whereby the condition of the refuse material on the grate may be observed. These ports are provided with doors 70 and the doors are provided with transparent panels 71 whereby observation of the wet garbage may be had without opening the incinerator compartment. If it is desired to agitate the material being dried from the exterior and without moving the scrapers 40 the doors 70 may be opened and a poker or rod inserted through the passageways 69. 100

The escape of steam and burnt gases from the compartment of the incinerator structure may take place through a flue 80 extending through the side wall 26 of the incinerator at a point above the uppermost sprockets 46. This flue may lead to the exterior of the structure or to the building chimney as desired. 105

In Figure 8 I show a modified form of 110 incinerator embodying the features of my invention and this form of incinerator is incorporated in the chimney structure of the building to be serviced. In this form of my invention the operating elements hereinbefore described are present but the grate shelf 33b has been extended upwardly to terminate below the chimney flue 90, it being understood that the garbage to be destroyed 115 is charged into the incinerator through 120

suitable doorways 91 formed in the chimney at each floor of the building. A passageway in the form of an auxiliary flue 92 is arranged to extend around the lower portion of the chimney where it joins the incinerator structure to discharge into the chimney at a point considerably above the top of the incinerator thus greatly decreasing the possibility of the incinerator becoming completely clogged by the garbage which accumulates on the grate shelf 33b.

From the foregoing description of my invention it will be apparent that I provide a very simple form of garbage disposal apparatus which will rapidly dehydrate or desiccate wet garbage and which is simple in form and which can be conveniently operated and maintained in a sanitary manner without the necessity of expert care.

20 I claim:

1. An incinerator comprising a rectilinear structure of a height and length in excess of its width, a partition forming a fire box at one end of the interior of the incinerator, an inclined partition extending from the first named partition to the rear wall of the incinerator structure, a fire grate disposed within said fire box compartment dividing the compartment into an ash pit and 25 a firing chamber and an inclined drying grate disposed above said inclined partition, the side walls of the incinerator having openings formed therein above the inclined partition and above the inclined grate and 30 other openings extending into the incinerator above and below the firing grate.

2. An incinerator having the interior thereof provided with an inclined partition, a drying grate disposed over said partition, 40 agitating means comprising endless chains operatively disposed adjacent the side walls of the incinerator, and scraper bars connected at their ends to the chains and movable over and under said grate bars, the 45 scraper bars being supported while beneath the grate on said inclined partition.

3. An incinerator having the interior thereof provided with an inclined partition, a fixed inclined grate disposed over said 50 partition, means guided for movement over the grate together with means for moving the first named means in a constant direction.

In testimony whereof, I hereunto affix my 55 signature.

EDWIN H. GRAVER.
